UNITED STATES PATENT OFFICE.

MARIE CATHERINE STEICHEN, OF NEW YORK, N. Y.

HAIR WAVER.

Application filed November 10, 1927. Serial No. 232,234.

This invention relates particularly to Marcel wavers of the general type covered in my Patent #1,646,173 of October 18th, 1927 and special objects of the invention 5 are to provide a hair waving form which will be particularly light and flexible so that it may be worn with comfort and readily adapted to the head of the user.

Other important objects of the invention 10 are to provide a hair waving device of simple, inexpensive construction and which can be readily adjusted to tension the hair sufficiently to produce the flat wave Marcel effect.

15 The foregoing and other desirable objects are attained in a preferred embodiment of the invention by making the hair waving form of flexible, covered wire, arranged with two strands in substantial parallelism to provide a body or back member, the respective strands having transverse loops projecting at the opposite sides of the body and the whole being bendable to tension and secure a lock of hair laced across the back and about 20 the loops.

Other novel features of the invention will appear as the specification proceeds.

In the accompanying drawing certain practical commercial embodiments of the invention are illustrated, but it is to be understood that the structure may be varied without departure from the true spirit and broad scope of the invention.

Figure 1 is a plan view of the waver in its 35 substantially flat form.

Figure 2 is a perspective view showing the transverse fingers of the waver bent to tension the lock of hair and the upper end of the waver bent back to secure the upper end 40 of the lock.

Figure 3 is a plan view showing the waver made up of a single continuous piece of wire and with the body of it held together by a wrapping instead of clips as in Figure 1.

45 The two strands of wire which form the back-bone and the transverse ribs or fingers of the device are designated 5, 6, and are shown each as a flexible metal wire 7 of copper, iron or the like, enclosed in a suitable covering 8 of insulating or fibrous material. These two strands of covered wire are secured together in substantial parallelism by encircling metallic clips such as indicated at 9 in Figures 1 and 2, by a wrapping 50 of tape 10 or the like, as in Figure 3, or by other suitable securing means and each

strand is formed with outwardly projecting double loops 11 arranged with the loops at one side staggered in relation to the loops at the opposite side of the structure. 60

In the first form of the invention shown, a sufficient number of the metallic clips are employed to hold these loops and the backbone of the device in shape and the wrapping of tape performs this same function 65 in the second form of the invention illustrated. If desired, adhesive means may be employed for securing the wires in this pre-formed relation.

The straight lengths of wire at the ends of 70 the device are bendable independently of the ribs or prongs to form flexible clips such as indicated at 12 in Figure 2, to secure the opposite ends of the lock of hair.

In some cases it is advantageous to construct the device of a single continuous length of wire, instead of two separate lengths, in which event the wire may be doubled upon itself at one end as indicated at 13 in Figure 3, the ends of the single 75 so length of wire being then secured together by a simple wrapping of wire or the like, as indicated at 14.

In use, the device may be applied to a lock of hair by bending the upper end of the 80 waver over the lock, close to the head, after which the hair may be laced in under the alternate prongs and across the back of the device, the free end of the lock being then secured by bending the lower end of the 85 device back over the lock in the same manner that the upper end was bent. The ribs or prongs may then be squeezed together more or less to tighten the hair and place a certain amount of tension on the same. The waver 90 may be allowed to remain in place over night, or as long as necessary, its flexibility preventing any injury to the wearer and holding the locks confined under tension in a 95 wave-like form. The device is released from the hair by simple bending back the flexible 100 end clips.

The securing of the two strands or lengths of wire alongside each other in substantial parallelism provides a relatively flat wide body and the covering on the wire forms a cushion, frictionally holding the hair and affording curved edges over which the hair will bend without breaking or other injury. These features in combination produce a 110 true flat wave Marcel effect, as distinguished from an ordinary curl.

The device is durable and relatively inexpensive. If the covering of the wire has a braided outer sheath as in the constructions illustrated, this braid exerts a frictional gripping effect, aiding in securing the hair and holding it under tension. The tape wrapping may be used alone or applied over the binding clips 9. For this purpose an elastic adhesive tape has been employed which can be stretched tightly and smoothly over and about the two wires and which seals itself in place by its adhesive character. In shaping and securing the wires in their side by side relation, the portions of the wire intermediate the loops form curved arches which aid in giving the desired wave to the hair.

What is claimed is:

1. A hair waving device comprising lengths of flexible wire secured together in substantially parallel side by side relation and having intermediate the ends of the same transversely bent loops projecting laterally from opposite sides of the device, said loops and the substantially parallel end portions of the wires being independently bendable over a lock of hair laced thereabout.
2. A hair waving device comprising two lengths of flexible covered wire arranged substantially parallel in side by side relation and each length having intermediate the opposite ends of the same outwardly projecting transverse loops and means securing said loops and the parallel end portions in

their pre-formed and side by side relation, 35 said parallel end portions and loops being independently bendable to clip and tension a lock of hair thereabout.

3. A hair waving device comprising two lengths of flexible covered wire arranged substantially parallel in side by side relation and each length having intermediate the opposite ends of the same outwardly projecting transverse loops and means securing said loops and the parallel end portions in 40 45 their pre-formed and side by side relation, said parallel end portions and loops being independently bendable to clip and tension a lock of hair thereabout, the portions of wire between the loops of each length of wire 50 forming curved arches to curve and shape the lock of hair engaged therein.

4. A hair waving device comprising lengths of flexible wire in substantially parallel side by side relation and having intermediate the ends of the same, transversely bent loops projecting laterally from opposite sides of the device and with the loops at one side of the device extending away from the loops at the opposite side of the device, clips 55 60 securing the two lengths of wire together and the base portions of the loops together in their pre-formed relations, the thus secured loops and the end portions of the lengths of flexible wire being independently bendable 65 over a lock of hair laced thereabout.

In testimony whereof I affix my signature.
MARIE CATHERINE STEICHEN.
